UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING-MACHINE SUPPORT.

Application filed September 15, 1921, Serial No. 500,853. Renewed July 7, 1925.

This invention relates to means for supporting typewriters and more particularly to drop-leaf typewriter-supports for use in connection with desks.

- 5 In the application of Cornelius B. Corcoran, Serial No. 375,491, filed April 21, 1920 (now Patent No. 1,418,701, dated June 6, 1922), it is proposed to use a drop-leaf or support in the form of an open frame 10 for the purpose of reducing the weight of the removable parts and of avoiding the noise, due to resonance, of a solid base or support which would act as a resonator and increase the noise of operation.
- 15 The main object of the present invention is to provide improved typewriter-supporting means open beneath the machine so that undue noise due to resonance will be avoided, and protecting means to extend across 20 said opening, said protecting means being light in weight, so as not to counteract the decrease in weight of the supporting means, and being easily removable for cleaning purposes.
- 25 According to the embodiment of the invention herein disclosed, the typewriter is placed on a rectangular open frame and secured thereto by suitable means, such as screws. The typewriter with the open frame 30 attached may then be slid into position in a support which may be in the form of a drop-leaf for a typewriter desk. The support comprises an open base portion on which the open frame may rest on side guides at sufficient distance apart to receive the open frame, the side guides being provided with inward extensions or flanges to overlie the sides of the open frame when the latter is slid into position on the base, the sliding 35 movement of the open frame being limited by suitable means at the rear of the leaf or support. The leaf may be pivoted on opposite sides to the end sections of the desk and may be connected in any suitable manner with the cover, so that when the cover is shifted to open position the typewriter will be in position for use, and when the cover is brought to closed position the typewriter will be in lowered position beneath the cover.
- 40 It will be evident that, although the drop-leaf has been rendered lighter than usual and noise due to resonance has been avoided by use of the open structure, the typewriter will be exposed to dust from beneath and 45 the waste or detritus resulting from erasures

and other causes will drop through and soil the clothes of the operator. To avoid such disadvantages, provision may be made of a protector in the form of an open frame with suitable material, such as cheese cloth, 60 stretched thereacross, and this protector may be slidably mounted on the lower side of the support or leaf so that it may be easily placed in position or withdrawn for the purpose of cleaning.

65 Other features and advantages will hereinafter appear.

In the accompanying drawings,

Figure 1 is a diagrammatic side view, 70 partly in section, showing my invention in connection with an Underwood standard typewriter.

Figure 2 is a front view, partly in section, of the lower part of the structure 75 shown in Figure 1.

Figure 3 is a perspective view of the open frame to which the typewriter is normally attached, the position of the typewriter thereon being indicated in broken lines.

Figure 4 is a perspective view, showing 80 the drop-leaf with the protector applied thereto.

A typewriter comprising keys 11, a platen 12, a traveling carriage 13, a frame 14 and feet 15 is placed on an open frame or base 16 so that the feet 15 rest on the sides 17. The typewriter frame 14 is provided with internally threaded lugs 18, and the frame 16 is provided with openings 19 immediately beneath the lugs, so that screws 20, inserted 85 through the openings 19, may be screwed into the threaded openings in the lugs 18 to hold the typewriter in position on the frame 16. The openings may be countersunk at their lower ends, so as to receive the heads 90 of the screws 20, and the screws 20 may be locked in position by means of lock-nuts 21 placed on the screws before the latter were 95 screwed into the lugs 18.

To support the frame 16, provision may 100 be made of a drop-leaf 22, pivotally mounted at 23 on the ends or drawer-sections of a desk 24, and the leaf 22 may be connected with a cover 25, so that, when the cover 25 is shifted to the position shown in Figure 105 4, the leaf 22 will be in substantially horizontal position, but when the cover is lifted and swung to position to close the opening in the top of the desk 24, the leaf 22 will be 110 swung downwardly, so as to carry the ma-

chine mounted thereon, beneath the cover 25. The leaf 22 comprises an open base 26 to receive the frame 16, side members or guides 27 mounted on the base 26 at a suitable distance apart to receive the frame 16, and a cross-bar 28 at the rear to limit the movement of the frame 16 rearwardly. Secured to the guides 27 by suitable means, such as screws 29, are angle irons 30, flanges 31 of which extend inwardly from the guides 27 so as to overlie the side edges of the frame 16 when the latter is slid into position on the base 26. As shown in Figure 1, the different parts of the leaf 22 are so positioned with reference to each other that, when the frame 16 is moved rearwardly into contact with bar 28, its front edge will lie flush with the front edge of the base portion 26. It will be evident that when the typewriter, with the open frame 16 attached thereto, is placed in position on the leaf or frame 22, the typewriter will be held firmly in position when the leaf is swung downwardly by the upward movement of the cover 25.

Although the leaf 22 and the frame 16 have both been made lighter by construction in open form, and the resonance which would result from a solid support has been avoided, it will be evident that the structure just described will have the disadvantages of permitting access of dust from beneath, and also permit dust and detritus resulting from erasures and other causes to drop on the clothes of the operator and soil them. To avoid such disadvantages provision may be made of a protector 32 in form of an open frame 33 having stretched thereacross a fabric 34 of any suitable material, such as cheese cloth, and the leaf 22 may be provided on its lower face with angle irons 35 secured thereto by any suitable means, such as screws 36, and having inwardly extending flanges 37 so spaced from the lower surface of the leaf that the sides of the frame 33 may be introduced between the same and the lower surface of the leaf 22. A flange or projection 38 extending downwardly from the base 26 of the leaf 22 limits the rearward movement of protector 32. It will be obvious that any waste matter dropping through the machine will be caught by the protector 32 and that when it is desired to clean the latter, it may readily be removed and cleaned.

Variations may be resorted to within the scope of the invention, and portions of the improvements may be used without others.

Having thus described my invention, I claim:

1. In combination, a base-piece for supporting a typewriting machine comprising an open frame having side members to receive the feet of the machine, said side members having openings, countersunk at their

lower ends beneath internally threaded lugs on the machine, and transverse members connecting said side members, and screws inserted upwardly through said openings and threaded into the internally threaded lugs 70 on the machine, the heads of the screws entering the countersunk portions of said openings; a second open frame having guides between which the first frame may slide, and flanges on said guides overhanging the first frame to prevent lifting thereof from the second; and a protector slidably supported by the second frame so as to extend across the openings of the two frames. 75

2. The combination with a base-piece in the form of an open non-resonant frame for supporting a typewriting machine, of a skeleton desk-drop to which the open base-piece is removably attachable, and a non-resonant, removable, dirt-collecting tray for closing the skeleton of the drop to prevent the dropping of dirt and oil from the machine onto the clothes of the operator. 85

3. The combination with a base-piece in the form of an open frame for supporting a typewriting machine, of a skeleton desk-drop to which the open base-piece is removably attachable, and a non-resonant dirt-collecting tray slidably mounted on the drop for closing the skeleton thereof. 90

4. The combination with a base-piece in the form of an open frame for supporting a typewriting machine, of a desk-drop, in the form of an open frame, to which the open base-piece is removably attachable, and a non-resonant dirt-collecting tray movably mounted on the drop for closing the frame thereof. 100

5. In combination, a rectangular open frame on which a typewriting machine is to be secured; a support for said frame pivoted at its front to the end portions of a desk having an opening in its top, said support comprising an open-base portion, side members spaced apart on said base-portion sufficiently to receive said frame, overhanging ledges to prevent lifting of said frame when slid therebeneath, and means to limit the rearward movement of said frame; and a protector to extend across the openings in 110 said frame and support.

6. In combination, a rectangular open frame on which a typewriting machine is to be secured; a support for said frame pivoted at its front to the end portions of a desk having an opening in its top, said support comprising an open base-portion, guide members spaced apart on said base-portion sufficiently to receive said frame, overhanging ledges to prevent lifting of said frame 120 when slid therebeneath, and means to limit the rearward movement of said frame; a protector to extend across the openings in said frame and support, and means whereby the protector may be quickly connected 125 130

with said frame and support and disconnected therefrom.

7. In combination, a rectangular open frame on which a typewriting machine is to be secured; a support for said frame pivoted at its front to the end portions of a desk having an opening in its top, said support comprising an open base-portion, guide members spaced apart on said base-portion sufficiently to receive said frame, overhanging ledges to prevent lifting of said frame when slid therebeneath, and means to limit the rearward movement of said frame; a protector to extend across the openings in said frame and support, and slide-ways on the lower face of said support to receive the sides of said protector.
8. In combination, a typewriter-support in the form of an open frame, means to position a typewriter on the support, and a non-resonant dirt-collecting tray slidably mounted on the open frame to close the opening therethrough when the typewriter is in position on the support.
- 25 9. In combination, a typewriter-support

in the form of an open frame, means to position a typewriter on the support, a non-resonant dirt-collecting tray mounted on the open frame to close the opening therethrough when the typewriter is in position 30 on the support, and means whereby the tray may be shifted on the support between its dirt-collecting position and a more accessible position for cleaning the same.

10. In a desk for a typewriting machine, 35 the combination of an open-work structure support for a typewriting machine, and a protecting device for receiving the detritus produced by the work-sheet erasures, including a frame enclosing suitable material 40 stretched thereacross and mounted on said open-work structure support with said suitable material underneath the openings in the open-work structure support, so as to receive the detritus of the work-sheet erasures that may fall through said openings when the machine is in its typewriting position.

JESSE A. B. SMITH.
